(57) **CLAIM**

The ornamental design for a bench seat for a vehicle, as shown and described.

DESCRIPTION

FIG. 1 is a front right elevated perspective view of a bench seat for a vehicle according to the present invention.

FIG. 2 is a front left perspective view of the bench seat shown in FIG. 1.

FIG. 3 is a rear left elevated perspective view thereof.

FIG. 4 is a rear right perspective view thereof.

FIG. 5 is a front view thereof.

FIG. 6 is a rear view thereof.

FIG. 7 is a left side view thereof.

FIG. 8 is a right side view thereof; and,

FIG. 9 is a top view thereof.
